(57) **CLAIM**

The ornamental design for a trailer front, as shown and described.

DESCRIPTION

FIG. 1 is a perspective of the trailer front shown in a condition of use.

FIG. 2 is a top view of the trailer front.

FIG. 3 is a right side view of the trailer front.

FIG. 4 is a left side view of the trailer front; and,

FIG. 5 is a rear view of the trailer front.

The broken lines depicting a trailer body and towing tongue illustrate environmental structure which forms no part of the claimed design. The broken lines on the surface of the article illustrate portions of the trailer front which form no part of the claimed design.
